FIG. VII.

UNITED STATES PATENT OFFICE

WILLIAM FINNEY HILLPOT, OF FRENCHTOWN, NEW JERSEY

INCUBATOR MECHANISM

Application filed March 26, 1928. Serial No. 264,822.

My invention relates to mechanism of the general character described and claimed in Letters Patent of the United States 1,489,597 granted to me April 8, 1924 and 1,545,425 granted to me July 7, 1925, wherein the means for supporting eggs include a vertical series of trays each supported by detachable connection with a plurality of vertically extending endless chain belts; whereby each tray is pivotally supported so that it may be tilted, to and from horizontal position, and inclined in either of two opposite directions to turn the eggs, with the object and effect of preventing the embryos from sticking to the shells; and each tray may be progressed vertically during the incubating period, from the place of introduction of the fresh eggs to the place of discharge of the hatched chicks. Each of said trays has freedom for such tilting movement, independently of its vertical movement of progression, but is capable of being contemporaneously tilted and progressed. That is to say, the portions of the mechanism respectively operative to effect the movements of tilting and progression may be operated at different times, or contemporaneously.

In the form of my invention shown in said Letters Patent, four such vertically extending endless chains are used to support the trays and means other than said supporting chains are employed to hold the trays in any position in which they may be tilted; such means being required because the trays are pivoted upon axes coincident with their centers of gravity and thus normally in unstable equilibrium. On the contrary, my present invention is operative with but three vertically extending suspension chains and the trays are supported, in stable equilibrium, in every position of inclination, by said chains; without the necessity of employing other holding means.

Moreover, the construction and arrangement of my present invention are such that all of the trays in a vertical series may be simultaneously tilted merely by relative movement of their supporting chains; which chains may be simultaneously moved to progress all of the trays in that series without

changing their inclination, or, as above contemplated, the chains may be shifted to contemporaneously effect tilting and progressing movement of the entire series of trays which they support.

My invention includes the various novel features of construction and arrangement hereinafter more definitely specified.

In said drawings; Fig. I is a fragmentary, diagrammatic, perspective view of a vertical series of egg trays supported by three vertical chains respectively suspended from chain wheels on three rotary shafts.

Fig. II is an end elevation of one of the trays shown in Fig. I, indicating the range of its inclination with respect to its pivotal connections with the two chains at the left hand edge thereof.

Fig. III is an elevation of the stop gears whereby the tilting movements of the trays are adjustably limited.

Fig. IV is an elevation of the worm gearing whereby the turning movements of the shafts shown in Fig. I are controlled.

Fig. V is an elevation of the stop dial and pins whereby the lowering movements of the trays are adjustably limited.

Fig. VI is a fragmentary perspective view of a portion of the side frame of one of the trays provided with pivotal suspension means.

Fig. VII is a fragmentary plan view of an incubator structure embodying my invention.

Fig. VIII is a plan view of the backing bar shown diagrammatically in Fig. I.

Referring to Fig. I; a vertical series of similar trays 1 are supported, with freedom for tilting and vertical bodily movement, by the three vertically extending flexible connectors 2, 3 and 4 which are conveniently endless chains, with which each of said trays 1 is adapted to be independently detachably connected by respective pivot means 5, 6 and 7 which may be of any suitable form adapted for detachable insertion in and pivotal engagement with an opening in such connectors, such as a link of a chain. For instance, as shown in Fig. VI, each of said pivot members may include a base flange 9 adapted

to be rigidly connected with the frame of the tray, conveniently by screws 10, and may have a hook member 11 which is offset from the side of the tray. The hooks of all of 5 said pivot members are preferably pointed in the same direction, to facilitate their engagement and disengagement with their respective connectors 2, 3 and 4.

The arrangement above described is such 10 that by relative movement of said chains, each of said trays 1 is adapted to be tilted upon its axis coincident with its pivot means 6 and 7, which are substantially at the left hand edge of the tray, and to and from horizontal position, and be inclined in either of 15 two opposite directions to the limit indicated in Fig. II.

It may be observed, with reference to Fig. II, that the common axis of the pivot means 20 6 and 7, being at the extreme edge of the tray; the latter is always overbalanced toward the right to stress the chain 2 downwardly by the weight of the contents of the tray and thus maintain each tray in stable 25 equilibrium upon its three points of support 5, 6 and 7. However, said points of support may be disposed otherwise than as indicated in Fig. I.

As indicated in Fig. I; the connectors 2, 30 3 and 4 are preferably endless chains respectively suspended from chain wheels 12, 13 and 14, respectively rigidly connected with rotary shafts 15, 16 and 17, and it is to be understood that when said shafts are 35 contemporaneously turned in the direction of the arrows upon said wheels, the entire series of trays may be bodily lowered; to thus progress each tray from the position of insertion of fresh eggs in the incubator, at the upper 40 portions of said chains, to the position of discharge of chicks from the trays at the lower portion of said chains. Also that the tilting movements of said trays above described may be effected by relative vertical movement 45 of said chains. For instance, the chain 2 may be shifted, up or down, while the chains 3 and 4 remain stationary, with the effect of tilting all of the trays 1, simultaneously, either upward or downward, and to 50 the extent indicated in Fig. II. Moreover, it is to be understood that the trays may be tilted contemporaneously with their downward progressive movement by proper movement 55 of said chain 2 in coordination with the other chains, as hereinafter described.

In Fig. IV, I have shown a convenient worm gearing mechanism for actuating said three shafts 15, 16 and 17, to coordinately effect the above contemplated movements 60 thereof. Said mechanism includes the metallic base frame 19 which may be rigidly connected with the vertical support 20 which may be a timber stud in or at a wall of the incubator inclosure in which said trays 1 65 are suspended. Said frame 19 has a journal

bearing 22 for the shaft 15, which carries said chain wheel 12, and said shaft is provided with the worm gear 23 in mesh with the worm 25 which has its shaft 26 journaled in the bearings 27 and 28 on said frame 70 19. The construction and arrangement is such that said worm holds said worm gear and the shaft 15 stationary except when said worm is turned, and such turning movement may be conveniently effected by the crank 75 wrench 30, indicated in Fig. IV, which is fitted to engage the squared wrench hold 31 upon the shaft of said worm.

Said worm shaft 26 has the spline key 34 for rotary engagement in the hub of the gear wheel 35 which is axially movable thereon but is normally pressed outwardly, by the spring 36 tending to shift said gear out of engagement with the gear 38. Said gear 35 may be provided with the set screw 39, or other suitable means, by which it may be secured either in the idle position shown or in mesh with said gear 38. Said gear 38 is rigidly mounted on the shaft 41 of the worm 42, which is journaled in the frame 43 which may also be rigidly connected with the same vertical support 20, and has the journal 45 for the shaft 16 upon which is rigidly mounted the worm gear 46 in mesh with said worm 42. Said shaft 16 carries the belt wheel 48 connected by the belt 49 with the belt wheel 50 on said shaft 17. Said belt 49 is conveniently a chain, but is referred to as a belt in the claims to avoid confusion with the tray suspension chains 2, 3 and 4 and connects said 95 shafts 16 and 17 for simultaneous turning movement.

The construction and arrangement above described are such that when the pair of gears 35 and 38 are in the disconnected position shown in Fig. IV; the trays may be tilted by turning movement of the worm 25, while the trays are prevented from bodily movement downward by the worm 42 remaining stationary. However, by turning both of said 105 worms 25 and 42 contemporaneously, said trays may be contemporaneously tilted and lowered and such contemporaneous movement may be effected, by independent turning movements of said worms, while the pair of gears 35 and 38 are disconnected, in the position shown in Fig. IV. However, when said gear 35 is shifted to the position indicated in dotted lines in Fig. IV and there secured, in mesh with the gear 38; turning 110 movement of either of said worms, conveniently effected by the crank wrench 30, effects simultaneous lowering movement of all of the chains 2, 3 and 4, while preserving the trays in whatever position of inclination they may 115 happen to be.

It is not desirable to tilt the trays more than forty-five degrees with respect to the horizontal plane, and I prefer to provide means to prevent overturning them. For in- 120 125 130

stance, as indicated in Fig. III, I provide the shaft 15 with the driving gear 52 in mesh with the idle stop gear 53 which has a circumferential series of sockets to receive the stop projections 54, which are conveniently cylindrical pins, which may be screw threaded at their inner ends to prevent accidental dislodgment thereof. The arrangement is such that when the trays are in horizontal position, said stop gear is in the position indicated in Fig. III and the range of tilting movement is limited by said stop pins 54 alternately encountering said driving gear 52. Of course, in that form of stop mechanism, it is necessary to remove said stop pins when it is desired to bodily lower the trays.

When, as is usual, it is desired to lower the entire series of trays, step by step, conveniently in steps equal to the spacing of the trays in the series; I find it convenient to provide stop means whereby the lowering movements of the trays are adjustably limited. A convenient form of such means is indicated in Fig. V, wherein the stop dial 56 is supported in stationary position, in concentric relation with the shaft 16 and has a circular series of six sockets 57 therein for stop pins 58 which are successively encountered by the stop projection 60 which is normally rigidly mounted on said shaft. When it is desired to lower said trays; the stop pin 58 with which the shaft stop projection 60 is in contact in Fig. V, is removed to permit turning movement of said shaft 16, and replaced when said shaft projection has passed its socket in said dial.

In order to facilitate engagement of the pivot means 7 on the trays 1 in proper relation with the links of the chain 4, which is most remote from the operator; I find it convenient to support the reach of said chain which is to be thus engaged, by means of a vertically extending backing bar 61, as indicated in Fig. I, which may be rigidly supported, in stationary position, by any suitable means, for instance, by brackets connecting it with the adjacent wall of the incubator inclosure. Said inclosure may be in the form of a room including walls with suitable bearing supports for said shafts 15, 16 and 17. However, the mechanism above described may be supported in any convenient manner by any suitable means.

It is to be particularly noted that the location of the flexible connectors by which the trays are supported at their front ends at the extreme opposite edges of those ends, facilitates the introduction of the trays between those connectors and into detachable engagement therewith; regardless of the specific construction or arrangement of the means whereby those connectors are, or may be, operated to effect tilting and lowering movements of the trays. Moreover, such location of the tray supports permits them to tempo-

rarily detachably engage and support a tray loading device upon which the trays may be slid to and from engagement with said flexible supports; which loading device is the subject matter of my copending application Serial No. 264,321 filed March 24, 1928, for Letters Patent of the United States.

Therefore, I do not desire to limit myself to the precise details of construction, arrangement or procedure herein set forth, as it is obvious that various modifications may be made therein without departing from the essential features of my invention, as defined in the appended claims.

I claim:

1. In an incubator egg tray supporting mechanism, the combination with a plurality of pendent flexible connectors, arranged to support a tray between them; of a tray having means affording respective points of suspension in engagement with said connectors; shafts arranged to move all of said connectors, simultaneously, to lower said tray and arranged to relatively move said connectors to tilt said tray; the axis of tilting movement of said tray being substantially at one edge thereof; whereby said tray may be selectively tilted up and down, while said axis is held stationary, and while said axis is being lowered, and may be lowered while preserving its angle of inclination.

2. In an incubator egg tray supporting mechanism, the combination with only three pendent flexible connectors, arranged to support a tray between them; of a tray having means affording three points of suspension in respective engagement with said connectors; shafts arranged to move all of said connectors, simultaneously, to lower said tray; and one of said shafts arranged to relatively move one of said connectors to tilt said tray; the axis of tilting movement of said tray being substantially at one edge thereof; whereby said tray may be selectively tilted up and down, while two of said connectors and said axis are held stationary, and may be tilted while all of said connectors and said axis are being lowered, and may be lowered, by simultaneous movement of said connectors, while preserving its angle of inclination.

3. Mechanism as in claim 1; wherein the connectors are endless chains, and including respective wheels fixed on said shafts and arranged to support said chains; and means connecting two of said shafts for simultaneous turning movement.

4. Mechanism as in claim 2; wherein each of two of said shafts has a worm gear rigidly mounted thereon; and two worms respectively in mesh with said worm gears; whereby said shafts are held stationary except when said worms are turned.

5. Mechanism as in claim 2; wherein each of two of said shafts has a worm gear rigidly

mounted thereon; two worms respectively in mesh with said worm gears; whereby said shafts are held stationary except when said worms are turned; and a pair of gears respectively carried by the two worms and relatively movable to and from mesh with each other; whereby all of said connectors may be simultaneously moved to lower said tray when said pair of gears are in mesh, and one of said worms may be turned, independently of the other, to tilt said tray, when said pair of gears are out of mesh.

6. In an incubator egg tray supporting mechanism, the combination with only three chains, arranged to support a tray between them, with two chains substantially at one edge of said tray and pivotally connected therewith; the other chain being pivotally connected with the opposite side of said tray; of shafts arranged to move said three chains together to lower said tray; and one of said shafts arranged to relatively move one of said chains to tilt said tray up and down, upon an axis substantially at one edge thereof; whereby tilting and lowering movements of said tray may be effected in coordinate relation.

7. In an incubator egg tray supporting mechanism, the combination with three chains, arranged to support a tray between them, with two chains at one side and one chain at the other side thereof; of means arranged to move said three chains together, to lower said tray; and arranged to relatively move one of said chains to tilt said tray, including three shafts having respective chain wheels rigidly connected therewith and respectively supporting said chains; means coordinately connecting said shafts, arranged to turn said shafts simultaneously, and permit the turning of one shaft independently of the other two shafts; whereby tilting and lowering movements of said tray may be effected in coordinate relation; said connecting means including worm gears on two of said shafts, two worms in respective cooperative relation with said worm gears; a pair of gears respectively carried by said worms; said pair of gears being relatively axially movable to and from mesh with each other; and one of said two shafts provided with worm gears connected with the third shaft, for simultaneous turning movement; whereby tilting and lowering movements of said tray may be effected in coordinate relation.

8. In an incubator egg tray supporting mechanism, the combination with three chains, arranged to support a tray between them, with two chains at one side and the third chain at the opposite side thereof; of three suspension means carried by said tray respectively detachably pivotally engaging said chains; means whereby said third chain may be raised and lowered to tilt said tray

up and down upon its pivotal connections with the other two chains, including a rotary shaft rigidly connected with a chain wheel, from which said third chain is pendent; and means limiting the tilting movement of said third chain, including a driving gear fixed on said shaft, an idler stop gear in mesh therewith, and two removable stop projections on said stop gear; said stop projections limiting the range of tilting movement, by alternate contact with said driving gear.

9. In an incubator egg tray supporting mechanism, the combination with three chains, arranged to support a tray between them, with two chains at one side and the third chain at the opposite side thereof; of three suspension means carried by said tray respectively detachably pivotally engaging said chains; means whereby said third chain may be raised and lowered to tilt said tray up and down upon its pivotal connections with the other two chains, including a rotary shaft rigidly connected with a chain wheel, from which said third chain is pendent; means limiting the tilting movement of said third chain, including a driving gear fixed on said shaft, an idler stop gear in mesh therewith, and two removable stop projections on said stop gear; said stop projections limiting the range of tilting movement by alternate contact with said driving gear; two other shafts respectively carrying chain wheels from which the other two chains are respectively suspended; and means cooperatively connecting said three shafts; whereby all of said chains may be simultaneously lowered to lower said tray, when said stop projections are removed from said idle gear.

10. In an incubator egg tray supporting mechanism, the combination with three chains, arranged to support a tray between them, with two chains at one side and the third chain at the opposite side thereof; of three suspension means carried by said tray respectively detachably pivotally engaging said chains; means whereby said third chain may be raised and lowered to tilt said tray up and down upon its pivotal connections with the other two chains, including a rotary shaft rigidly connected with a chain wheel, from which said third chain is pendent; two other shafts respectively carrying chain wheels from which the other two chains are respectively suspended; means cooperatively connecting said three shafts; whereby all of said chains may be simultaneously lowered to lower said tray; and means adjustably limiting such lowering movement, including a stop projection carried by one of said shafts and a second stop projection movable to and from the path of said first stop projection.

11. In an incubator egg tray supporting mechanism, the combination with three chains, arranged to support a tray between

- them, with two chains at one side and the third chain at the opposite side thereof; of three suspension means carried by said tray respectively detachably pivotally engaging 5 said chains; means whereby said third chain may be raised and lowered to tilt said tray up and down upon its pivotal connections with the other two chains; including a rotary shaft rigidly connected with a chain wheel, 10 from which said third chain is pendent; means limiting the tilting movement of said third chain, including a driving gear fixed on said shaft, an idler stop gear in mesh therewith, and two removable stop projections 15 on said stop gear; said stop projections limiting the range of tilting movement, by alternate contact with said driving gear; two other shafts respectively carrying chain wheels from which the other two chains are 20 respectively suspended; means cooperatively connecting said three shafts; whereby all of said chains may be simultaneously lowered to lower said tray, when said stop projections are removed from said idle gear; and means 25 adjustably limiting such lowering movement, including a stop projection carried by one of said shafts and a second stop projection movable to and from the path of said first stop projection.
- 30 12. In an incubator egg tray supporting mechanism, the combination with a plurality of endless flexible connectors, arranged to support a vertical series of trays between them; wheels from which said connectors 35 are respectively pendent; rotary shafts on which said wheels are respectively fixed; and means whereby said trays may be bodily lowered, and tilted; including worm gears on respective shafts, and worms in mesh with said 40 gears.
13. Mechanism as in claim 12; including means adjustable to cooperatively connect said worms; whereby said worms may be turned simultaneously to lower the trays, and 45 be turned relatively to tilt the trays.
14. Mechanism as in claim 1; wherein the connectors are endless chains, and including respective wheels fixed on said shafts and arranged to support said chains; and means 50 connecting two of said shafts for simultaneous turning movement, including an endless belt.
15. In an incubator egg tray supporting mechanism, the combination with two rotary 55 shafts carrying pendent flexible connectors, adapted to detachably engage and support trays; of worm gears fixed on respective shafts; worms respectively in cooperative relation with said worm gears; a pair of gears 60 respectively carried by said worms and relatively movable to and from meshed relation; and spring means arranged to normally hold said pair of gears out of mesh; whereby said shafts are prevented from turning, while said 65 worms are stationary, and may be simultane-
- ously turned, by rotation of either of said worms, while said pair of gears are in mesh; and one of said shafts may be turned while the other is stationary, when said pair of gears are out of mesh; a shaft carrying a flexible connector arranged to detachably support the rear end of a tray, and means connecting said shaft and one of said worm carrying shafts; and whereby, when said trays are connected to said connectors, said trays 70 are tilted when only one worm carrying shaft is turned, and are moved vertically when said gears are in mesh and turned.
- In testimony whereof, I have hereunto signed my name at Philadelphia, Pennsylvania, this Twenty-second day of December, 1927.
